United States Patent Office

Des. 184,994
Patented Apr. 28, 1959

184,994

SWEeper HOSE SUPPORT OR THE LIKE

John Frohman, Cincinnati, Ohio, assignor of one-half to
J. Warren Kinney, Jr., Cincinnati, Ohio

Application July 21, 1955, Serial No. 37,066

Term of patent 14 years

(Cl. D91—1)

Fig. 1 is a front perspective view of a sweper hose support or the like, showing my new design.

Fig. 2 is a rear view thereof.

Fig. 3 is a side view thereof.

Fig. 4 is a bottom view thereof.

I claim:

The ornamental design for a sweper hose support or the like, as shown.
